(57) **CLAIM**

I claim the ornamental design for a measuring spoon system, as shown and described.

DESCRIPTION

FIG. 1 is an exploded perspective view of a measuring spoon system, illustrated with an implement and a measuring spoon in a detached configuration, showing my new design;

FIG. 2 is a perspective view of the invention, illustrated with the implement and the measuring spoon in an attached configuration;

FIG. 3 is a front elevational view of the measuring spoon of the invention;

FIG. 4 is a rear elevational view of the measuring spoon of the invention;

FIG. 5 is a right-side elevational view of the measuring spoon of the invention;

FIG. 6 is a left-side elevational view of the measuring spoon of the invention;

FIG. 7 is a top plan view of the measuring spoon of the invention;

FIG. 8 is a bottom plan view of the measuring spoon of the invention;

FIG. 9 is a right-side elevational view of the implement of the invention;

FIG. 10 is a left-side elevational view of the implement of the invention;

FIG. 11 is a front elevational view of the implement of the invention;

FIG. 12 is a rear elevational view of the implement of the invention;

FIG. 13 is a top plan view of the implement of the invention; and,

FIG. 14 is a bottom plan view of the implement of the invention.

The measuring spoon and implement are shown separately for clarity of illustration.
